UNITED STATES PATENT OFFICE.

WILLIAM HENRY JOSEPH HIPPLE, JR., OF PHILADELPHIA, PENNSYLVANIA.

CIGARETTE EXTINGUISHER.

Application filed July 8, 1921. Serial No. 483,294.

To all whom it may concern:

Be it known that I, WILLIAM H. J. HIPPLE, Jr., a citizen of the United States, residing at Philadelphia, in the county of Philadelphia and State of Pennsylvania, have invented new and useful Improvements in Cigarette Extinguishers, of which the following is a specification.

This invention relates to an improvement 10 in ash trays for tobacco smokers and is arranged to provide an efficient receiver for the reception of cigar butts, ashes from pipes, cigars, and cigarettes, as well as to provide means for holding cigarettes, the 15 holder being arranged to support a lighted cigarette without extinguishing it or to choke the lighted end, extinguish it and thereby prevent further smoke arising therefrom.

Another object of my invention is to 20 provide such a receiver which can readily be cleansed and maintained in a sanitary condition.

The device may comprise a tray of dish 25 form, preferably of glass or other material which is non-combustible, and which has a surface which can readily be cleaned and a ring preferably of metal, such as brass, which is non-combustible, ornamental, and 30 which can also readily be cleaned.

In the accompanying drawings, forming 35 part of this specification:—

Figure 1 is a perspective showing a holder 40 constituting a desirable embodiment of my invention as superimposed on a surface which may be that of a table, bar or the like.

Figure 2 is a diametrical section of the 45 said holder.

Figure 3 is a diametrical section showing 50 a holder of the type indicated as disposed in a tray.

Similar numerals designate corresponding 55 parts in Figures 1 and 2 to which reference will first be made.

The holder of the figures indicated is of 60 general annular form, and may be made of metal, porcelain or any other material compatible with the purpose of my invention, the invention residing not in the material of 65 the holder but in the materially advantageous characteristics of the holder as will now be pointed out. The holder comprises a body 1, a plurality of sockets 2 therein

adapted to receive the lighted ends of cigarettes and preferably tapered downwardly as 55 illustrated, and a bevel or inclined surface 3 at the inner lower corner of the body 1. At its lower edge 4 the body 1 is adapted to rest on a surface 5 which may be that of a 60 table or bar or may be the upper side of the bottom of a tray 6, as shown in Figure 3. The lower ends of the sockets 2 extend through the said beveled or inclined surface 3 and hence it will be manifest that the lower ends of the sockets will always be in 65 spaced relation to the surface on which the holder is placed, with the result that free access is afforded for air to the lower ends of the sockets 2. This free admission of air to the lower ends of the sockets 2 is materially 70 advantageous for the reason that when the lighted end of a cigarette is temporarily placed by a smoker in one of the sockets 2, by lightly dropping it therein the air acting through the lower end of the socket will 75 serve to maintain the cigarette lighted. It will also be understood that the clearance afforded between the lower ends of the sockets 2 and the supporting surface is further 80 materially advantageous inasmuch as it enables ashes to freely pass from the sockets 2 to the supporting surface and in that way precludes the filling of the sockets 2 with 85 ashes.

Manifestly when my novel holder is 85 superimposed upon a table, bar or other surface as shown in Figures 1 and 2, the annular body 1 will serve to confine the ashes that are received within the holder from the lower ends of the sockets 2, so that flying 90 of the ashes will be effectively prevented, and at suitable intervals the holder may be lifted from the surface 5 for the ready removal of the confined mass of ashes.

I illustrate the periphery of the body 1 95 as convex in vertical section, and I also illustrate the said body 1 or holder with the convex outer side as disposed in a correspondingly shaped tray 6, Figure 3. I would have it distinctly understood, however, that the convexity of the periphery of the holder and the concave shape of the inner side of the side wall of the tray are not of the essence of my invention inasmuch as the periphery of the holder and the inner 100 side of the side wall of the tray may be 105

straight or of any other appropriate configuration without affecting my invention as claimed.

The lower face of the cigarette holder converges upwardly and inwardly so that the lower ends of the sockets around said face will be clear of a flat supporting surface, and thereby provide sufficient clearance for the entrance of air to the lower ends of the sockets, as well as to provide ash space below the sockets. The ashes, etc., within the holder will be retained by the annular apex formed by the periphery and lower face. This clearance is also provided when the holder is positioned in a dish-shaped tray, having a relatively flat bottom and a side wall conforming to the periphery of the holder.

Having described my invention, what I claim and desire to secure by Letters-Patent, 20 is:—

A cigarette extinguisher comprising a device having inner, outer, upper and lower faces, each face forming a junction with two of the other faces, there being a plurality of 25 tapered sockets extending through the device from the upper to the lower faces, the lower face being so shaped that the sockets open at their lower ends above a plane extending through the lowest portion of the lower 30 face to form an air space communicating with the bottoms of the sockets when the device is placed on a plane surface.

In testimony whereof I affix my signature.

WILLIAM HENRY JOSEPH HIPPLE, JR.
